REFRIGERANT DISTRIBUTOR

Joseph D. Lear, Buffalo, N. Y., assignor to Feeders
Manufacturing Company, Inc., Buffalo, N. Y.Original application March 4, 1937, Serial No.
129,019. Divided and this application February
14, 1939, Serial No. 256,273

6 Claims. (Cl. 62—126)

This invention relates to refrigeration systems, and it has particular reference to the provision of means for distributing liquid refrigerant to a plurality of expansion coils.

5 The invention is applicable in systems where a plurality of separate refrigeration coils are supplied from a single source through an inlet manifold, and it consists of a distributor which apportions the refrigerant supply to the feed conduits 10 which lead to the several coils. In the embodiment of the invention illustrated herein, there is provided a unit with a plurality of ports which, through valve structures, may be varied to suit the demands of the several coils. Undesirable 15 inequalities or equalities of feeding may therefore be eliminated.

The invention is more specifically described in the accompanying specification, reference being had to the drawing, wherein:

20 Fig. 1 is a side elevation of a distributor unit with portions shown in vertical section. An associated refrigerant coil unit is shown diagrammatically.

Fig. 2 is a plan thereof.

25 Fig. 3 is an enlarged fragmentary section on the line 3—3 of Fig. 1.

Fig. 4 is a side elevation of a control valve.

In Fig. 1 a feed or distributor unit 10 is shown organized with a refrigerant evaporator unit 11 of a well known type consisting of finned tube coils 12, 13, 14, 15, 16, 17, disposed in parallel vertical rows and having inlet or feed tubes 12a, 13a, 14a, 15a, 16a, 17a leading to the control unit 10. The outlet terminals of the coils lead 30 to a common discharge header 18, which communicates with the suction side of a refrigeration system through a suction pipe 20.

The unit 11 is mounted in an air duct 21, and the stream of air which is forced therethrough 35 passes through the successive coil structures and is progressively cooled to the desired temperature. As is well known in the art, the first coil 17 impinged by the air bears the heaviest refrigerating load, which load is diminished progressively in the succeeding coils, and accordingly the coils will require a directly proportional supply of refrigerant, which, in the present invention, is accurately metered to the feed tubes through the distributor unit 10.

40 The unit 10 includes a housing fabricated of a cylindrical body 22 and an enclosing shell or cup 25. The body 22 is provided with upper and lower circular flanges 23 and 24, while the cup 25 contains an opening in its closed end 27, which 45 is fitted over and brazed to the upper flange 23.

The open end of the shell is subsequently spun over and brazed to the lower flange 24, as indicated by the numeral 28, to form a sealed annular reservoir or compartment 30 about the body 22. The reservoir is supplied with refrigerant 5 through an inlet pipe 29 which is fitted in a drilled inlet boss 31 in the flange 24. The pipe may lead to any of the well known control valve units used in refrigeration systems for controlling the quantity of refrigerant directed to the 10 coils. For exemplary purposes, a thermostatic expansion valve V is shown interposed in the pipe line 29.

The body is drilled to provide six equally spaced vertical formations, each comprising an opening 15 33 for receiving one of the feed tubes, a communicating vertical valve chamber 34, a valve stem opening 35, and a tapped hole 36. The body is slotted to provide elongated vertical ports 37 each leading into a valve chamber 34, and thus providing communication between the reservoir 30 and the feed tubes of the evaporator unit 11.

The port areas are controlled by manually operable valve devices which may be of any of the numerous forms known in the art. I prefer, however, to utilize a cylindrical valve 40, which is formed with a flattened side 41. Each valve is rotatably mounted within a valve chamber 34 and it is formed with a stem 42 of reduced diameter which projects through the opening 35. 30 The tapped hole 36 receives a nut 43 which retains a packing ring 44 in tight engagement with the stem 42, and thus prevents gas escape about the stem. The projecting portion of each stem receives an operating handle 46 which overlies 35 an escutcheon plate 47 which is soldered to the end 27 of the shell 25. The plate 47 is formed with dial markings 48 for each handle 46 to indicate the open and closed position of the valve.

When it is possible to place the unit 10 above 40 the level of the coil unit 11, I have found it advantageous to reduce the head pressure in the reservoir 30 and valve chambers 34, so that a close simulation of a gravity feed through the valves is obtained. This is effected by providing a diametrical hole 50 in the body 22, which communicates with the upper extremity of the reservoir 30. This hole communicates with a vertical hole 51 which receives a gas escape tube 52 leading to the discharge header 18. Thus, gases accumulating in the reservoir 30 are discharged directly into the header 18, and accordingly the pressure in the reservoir is reduced so that a gravity flow of the liquid refrigerant is obtained. In other types of installations, it may be desir-

able to reduce the effective area of the tube 52 or to close it entirely; therefore I provide a control valve C therein, which may be of any known type.

It will be apparent that after a preliminary setting of the valves on the basis of the computed capacity of the various coils, a more accurate setting thereof may be obtained by observation of the sweat or dew points on the coils, so that under constant air flow conditions the coils may operate with maximum efficiency. In the drawing, the valve of the last coil 12 is closed, so that the coil is rendered completely inoperative, while the remaining coils, starting with the coil 17, are supplied with progressively diminishing volumes of refrigerant. Thus, not only may the coils be supplied with precise volumes of refrigerant, but any desired number of coils may be shut down when the operation of the system under a reduced load is deemed economical.

The structure of the valves and ports is such that the refrigerant escapes from the reservoir 30 through narrow, vertical slits, and, as a result, the liquid refrigerant will continue to rise in the reservoir until it attains a level where the covered port areas are substantially equal to the orifice area of the escape port of the thermostatic expansion valve V, which supplies the reservoir. In view of the proportional characteristics of the port openings, it will be apparent that even if the unit 10 is installed a few degrees out of a true vertical position, the error reflected on the ports will be extremely small.

The applicability and value of the invention will be apparent by considering the conditions which arise in feeding refrigerant to a plurality of coil passages from a common source. Heretofore, it was customary to provide each coil passage with its own thermostatic expansion valve. Due, however, to initial cost, and the difficulty of balancing a large number of thermostatic valves against each other, this method has met with universal criticism. Recourse was then made to static distributors connected between the coil passages and the discharge side of a single valve. The object of a substantial number of designs along this line has been to equalize the flow of refrigerant to each coil, thus, if there were six coil passages, the distributor would be provided with six equal sized discharge ports.

However, experience has shown that this proposal does not give the results desired. One reason is that a flowing and boiling mass of refrigerant will not readily divide itself uniformly in passing through a number of simple orifices, such as holes drilled in a plate. Another reason is that many coils are so installed that the heat load on one section is not equal to the heat load on another, and therefore absolutely uniform distribution of refrigerant, if obtained in the first instance, would not be wanted. Whenever the quantity of refrigerant is divided and proportioned improperly with respect to the heat load on the several coils, the coil efficiency must be reduced to the effectiveness of the most inefficient section, to avoid flooding of the compressor.

The present invention, while eliminating the necessity for independent thermostatic valves, nevertheless permits of independent setting of the several ports leading to the coil sections, after the unit is installed. By observing the degree of superheat on the suction side of each unit, and adjusting the valve handles 46 as in-

dicated, each coil section may then be brought to the same degree of effectiveness, and irregularities due to variations in internal resistance, port apertures, and coil loading may be compensated for.

The present application is a division of my copending application Serial No. 129,019, filed March 4, 1937. It will be understood that while the invention has been described with reference to a single embodiment, its novel and useful features may be embodied in other forms and arrangements, and therefore it is intended that the scope of the invention should be determined by reference to the following claims.

I claim:

1. A distributor device for supplying refrigerant to a plurality of cooling coils comprising a housing including a compartment connected to a refrigerant supply source, a plurality of vertically disposed valve chambers in the housing, one end of each chamber being connected to a feed conduit for a cooling coil, vertical ports in the housing connecting each chamber with said compartment, an elongated valve in each chamber disposed therein to control the port area, each valve having a stem extending through the housing and supplied with an adjusting lever.

2. A distributor device for supplying refrigerant to a plurality of cooling coils comprising a housing including a compartment connected to a refrigerant supply source, a plurality of vertically disposed cylindrical valve chambers in said housing, one end of each chamber being connected to a feed conduit for a cooling coil, a vertical slot in the housing entering each chamber and constituting ports for connecting the chambers to said compartment, a cylindrical valve rotatably mounted in each valve chamber and formed with an axial flattened side, each valve having a stem extending through the housing and supplied with an adjusting lever.

3. A distributor device for supplying refrigerant to a plurality of cooling coils comprising a housing including a compartment connected to a refrigerant supply source, a plurality of vertically disposed cylindrical valve chambers in said housing, one end of each chamber being connected to a feed conduit for a cooling coil, a vertical slot in the housing entering each chamber and constituting ports for connecting the chambers to said compartment, a cylindrical valve rotatably mounted in each valve chamber and formed with an axial flattened side, each valve having a stem extending through the housing and supplied with an adjusting lever, and indicia groups formed on the exterior of the housing for cooperation with each lever.

4. A distributor device for supplying refrigerant to a plurality of cooling coils comprising a vertically disposed body having a circular radial flange on its lower extremity and a cup shaped shell having an opening in its end wall through which the upper extremity of the body projects, the remainder of the shell enclosing the body with the open end of the shell secured to said flange, a plurality of vertically disposed valve chambers in said body, the lower end of each chamber being connected to a feed conduit for a cooling coil, said body being formed with vertical port slots each establishing communication between a chamber and the space enclosed by the shell, an elongated valve in each chamber disposed therein to control the port area, each valve having a stem extending through

the body and supplied with an adjusting lever.

5. In a refrigeration system having a plurality of independent cooling coils and a refrigerant supply conduit including an automatic control valve therein, a distributor comprising a housing adapted to receive volumes of refrigerant from said conduit under control of the control valve, distributor conduits communicating with the housing and each being adapted for connection to one of the coils, port means in the housing for admitting refrigerant from the housing to each of the conduits, and manually adjustable valve means for controlling the proportionate quantity of refrigerant passing through each of said port means into said coils, whereby by manual setting of said valve means the quantity of refrigerant supplied to the housing by the automatic control valve may be proportioned to the heat load on each coil and to the total quantity of refrigerant thus supplied.
10. In a refrigeration system having a plurality of cooling coils and a refrigerant supply conduit including an automatic control valve there-
15. In a refrigeration system having a plurality of cooling coils and a refrigerant supply conduit including an automatic control valve there-

in, a distributor comprising a housing adapted to receive volumes of refrigerant from said conduit under control of the control valve, distributor conduits communicating with the housing and each being adapted for connection to one of the coils, port means in the housing for admitting refrigerant from the housing to each of the conduits, and manually adjustable valve means for controlling the proportionate quantity of refrigerant passing through each of said port means into said coils, whereby by manual setting of said valve means the quantity of refrigerant supplied to the housing by the automatic control valve may be proportioned to the heat load on each coil and to the total quantity of refrigerant thus supplied.
